DROP HAMMER

William H. J. Fitzgerald and Reginald P. Fitzgerald, Braintree, Mass., assignors to Pneumatic Drop Hammer Company, Roxbury, Mass., a corporation of Massachusetts

Application July 8, 1937, Serial No. 152,544

8 Claims. (Cl. 113—38)

This invention relates to improvements in drop hammers and the principal object of the invention is to provide a drop hammer construction in which the hammer is reciprocably mounted in guides in a suitable frame, with means for lifting the hammer, and means for releasing the hammer when raised to permit it to drop and having means for insuring equalization of movement of the guided portions of the hammer throughout the lifting movement thereof.

In usual drop hammer constructions the weight of the hammer is substantially uniformly distributed with respect to a central vertical axis and the ends of the hammer are guided in vertical ways or upon vertical columns. The vertical lifting force is applied in or approximately in the direction of the vertical axis of the center of gravity and as a consequence the hammer may be lifted and dropped without any substantial binding action between the ends of the hammer and the guides therefor.

Where, however, the hammer is unsymmetrically weighted, as for example by the attachment thereto of one of the members of the complementary dies, in which the weight of one portion of the die, which is carried by the hammer, very considerably exceeds the weight of other portions of the die, the hammer will tilt and bind in its guides when lifted by force which is applied at a point or points not in the vertical axis of the center of gravity, so that the hammer will not drop properly with respect to the complementary die, or will so bind on the guides as to prevent operation of the hammer at all.

An object of the present invention is to provide means operable during the lifting movement of the hammer to transmit a lifting force or lifting forces, which are applied to the hammer, at a point or points remote from the vertical axis of the center of gravity which will equalize the rates of movement of the guided portions of the hammer in such manner that the hammer will be lifted vertically without binding upon the guides and which also will insure proper maintenance of the position of the hammer during the dropping movement thereof.

One of the principal objects of the invention is to provide a drop hammer construction in which the hammer and anvil or complementary dies carried respectively by the hammer and anvil are of much greater area and in which drop hammers of much greater weight may be employed than in previous drop hammer constructions, such, for example, as drop hammers and dies for shaping fenders and other parts of automobiles,

metal aeroplane wings, or other large areas of metal or the like, and particularly those in which the dies are of irregular contour and unsymmetrically distributed weight.

5 A further object of the invention is to provide a drop hammer construction in which the hammer is lifted by a plurality of lifting forces applied to different portions of the hammer, with means for so transmitting portions of such lifting forces that the resultants thereof will raise the hammer vertically and uniformly throughout its entire area.

10 A further object of the invention is to provide a drop hammer construction of the character above specified in which the lifting force or forces are applied to the hammer by fluid pressure operated means acting upon the hammer at a point or points remote from the vertical axis of the center of gravity of the hammer, in combination with means for so distributing the lifting force or forces as to insure uniform rates of movements of the guided portions of the hammer which will avoid binding of the hammer upon the guides.

15 Another object of the invention is to provide a drop hammer construction in which the hammer is pushed upwardly by a fluid pressure operated means acting upon the end portions of the hammer.

20 Another feature of the invention relates to novel fluid pressure actuated mechanism for controlling the admission of fluid simultaneously to the cylinders of the lifting mechanism.

25 Another object of the invention is to provide a drop hammer for die forging in which the hammer die is cast upon the hammer and a method for producing such a construction.

30 Another object of the invention is to provide pneumatically operable means for effectively cushioning the upward movement of the hammer when lifted which will prevent abrupt arrest of the hammer and consequent jarring which would tend to injure the structure.

35 These and other objects and features of the invention will more fully appear from the following description and the accompanying drawings, and will be particularly pointed out in the claims.

40 Preferred embodiments of the invention are illustrated in the accompanying drawings, in which:

45 Fig. 1 is a front elevation of a drop hammer embodying the invention in which the hammer is lifted by two pneumatically operated cylinders and pistons, the piston rods of which apply lifting forces at the ends of the hammer, the

mechanism for equalizing the movements of the ends of the hammer being omitted.

Fig. 2 is a similar view showing the frame construction in dotted lines, but illustrating in full lines the hammer, the lifting mechanism therefore, and the equalizing mechanism for insuring equal rates of movement of the ends of the hammer;

Fig. 3 is a plan view of the construction shown in Fig. 2, the frame being illustrated in dotted lines;

Fig. 4 is an end elevation of the construction illustrated in Fig. 2, the frame being shown in dotted lines;

Fig. 5 is a detail elevation, viewed from the rear, showing the valve controlling mechanism for admitting fluid under pressure to the lifting cylinders;

Fig. 6 is a detail elevation of the construction shown in Fig. 5, viewed from the left toward the right;

Fig. 7 is a detail vertical sectional view showing the admission and exhaust valves in their relative positions for admission of fluid under pressure to the lifting cylinders;

Fig. 8 is a similar detail sectional view showing the admission and exhaust valves in their relative positions for release of fluid under pressure from the lifting cylinders to permit the hammer to drop; and,

Fig. 9 is a detail view showing the contour of the adjustable exhaust port for regulating the rate at which fluid under pressure is released from the cylinders thereby controlling the speed of descent of the hammer;

Fig. 10 is a detail view, partially in vertical section, on line 10—10 Fig. 11 of a drop hammer construction illustrating the manner in which the hammer die is cast upon a hammer of the type illustrated herein; and,

Fig. 11 is a plan view of the hammer construction illustrated in Fig. 10.

The drop hammer construction as illustrated in Fig. 1 comprises a heavy integral bed 1 supporting an anvil 2 upon which an unsymmetrical die 3 is mounted and a frame comprising pairs of vertical end standards 4 and 5, each pair being integrally connected at their upper ends and each standard is provided with a pair of guides 6 and 7 for the hammer. The pairs of standards are connected at their upper ends by a transverse beam 8.

The hammer 9 is provided with extended guiding members 10 and 11 which are complementary to and slidably mounted upon the guides 6 and 7 respectively. The preferred form of hammer, which is illustrated herein as adapted for die-shaping long articles of considerable width, is of rectangular form and is provided with a central upwardly extending boss 12 with vertical webs 13 and 14 extending radially therefrom to the guides 10 and 11 and other webs 15 extending to the edge of the hammer at right angles to the longitudinal axis thereof. The ends of the hammer are provided with extensions 16 and 17 which project outwardly between and beyond the respective pairs of guides 10 and 11 and the lifting forces for raising the hammer are applied to such extensions. The hammer as illustrated has secured to it a die 18 which is complementary to the anvil die 3 and as will be observed is of much greater weight at one end than the other.

The complementary dies may be of any suitable form and shape and may be of steel, but

where a limited number of parts are to be shaped the dies may be made of relatively soft metal, usually of different hardness, such as an anvil die of zinc or bronze composition and a complementary die of lead or other relatively softer metal.

The anvil die may be constructed by forming a matrix of plaster of Paris or the like and shaping the operating face to the desired contour and ornamentation. The harder metal for the anvil die may then be cast upon this matrix. When the matrix is removed the die may be turned over and suitably secured to the anvil.

By the present invention the hammer die may then be cast directly upon the hammer itself by a method hereinafter to be described.

By reason of this invention a hammer die is produced which is complementary in all respects to the anvil die and adapted to register accurately with the same during the period of its use. Such dies may be used for shaping relatively ductile metal, such as aluminum, or relatively thin sheets of steel and the like for a more or less limited number of times. The dies constructed in this manner are used particularly in the production of large die-shaped pieces where a limited number of different sizes or different contours are frequently required.

In such drop hammer constructions the vertical axis of the center of gravity of the hammer is ordinarily remote from the central vertical axis of the hammer and inasmuch as one end of the hammer is of greater weight than the other end or portion of the hammer, there will be a tendency of the hammer to bind upon its guides as the hammer is lifted, by a force or forces applied to the hammer at points out of alignment of the vertical axis of the center of gravity of the hammer.

The particular drop hammer construction illustrated herein is designed for the shaping of large areas of metal and the hammer may be of several tons weight. In order properly to lift such a hammer pneumatically operated means are preferably provided for simultaneously lifting both ends of the hammer, with means for equalizing the rate of movement of the guided portions of the hammer which will prevent binding of the hammer upon its guides. The lifting mechanism illustrated comprises a pair of vertical pneumatic cylinders 19 and 20 which are located at the ends of the base and are provided with pistons having respectively piston rods 21 and 22, the upper ends of which engage the under faces of the extensions 16 and 17 of the hammer. Suitable means hereinafter to be more fully described are provided for simultaneously admitting fluid under pressure to the lifting cylinders 19 and 20 and for releasing the fluid pressure to permit the hammer to drop.

Suitable force-transmitting means are provided which act upon movement of the hammer to cause equality of movement of both guided ends of the hammer. In the particular construction illustrated such force-transmitting means comprises one or preferably a plurality of taut inextensible flexible members each of which is connected to both ends of the hammer, with means for guiding the respective sections of each flexible member adjacent its attachment to the hammer in opposite vertical directions so that if a preponderance of force is applied to the lighter portion of the hammer, such portion of said force will be transmitted to the heavier portion of the hammer as to cause both ends of the hammer to

be lifted at an equal rate of speed and conversely if a preponderance of force is applied to the heavier portion of the hammer the lighter portion of the hammer will be caused to move upwardly at the same rate of speed.

In the particular construction illustrated a taut inflexible member 23 is rigidly secured at one end to a boss 24 upon the extension 17 of the hammer and has a section 25 extending vertically upwardly therefrom over a sheave 26 which is mounted upon the beam 8 and thence horizontally over a sheave 27 mounted upon the other end portion of the beam 8, thence downwardly against a guide sheave 28 which is mounted upon the upper end portion of the standard 4, thence downwardly around a sheave 29 which is mounted on the lower portion of the standard 4, thence upwardly through a boss 30 to which its end is adjustably secured, so that this end portion 31 of the inflexible member 23 as well as the end section 25 extends vertically. The sheaves 26 and 29 are so positioned as to direct the end sections 25 and 31 respectively vertically a distance at least as great as the distance through which the hammer drops.

While a single taut inextensible flexible member may be employed, desirably a plurality of such members are embodied in the machine. As illustrated herein a complementary taut inextensible flexible member 32 has one end connected to a boss 33 on the extension 17 of the hammer. The end section 34 thereof extends vertically downwardly around a sheave 35 mounted on the lower portion of the standard 4, thence upwardly along a guiding sheave 36 mounted upon the upper portion of the standard 4, thence over a sheave 37 which is mounted upon the beam 8, thence horizontally over a sheave 38, then vertically downwardly, the end section 39 being adjustably connected to a boss 40 on the extension 16 of the hammer.

By reason of the fact that each of the complementary taut inextensible flexible members is connected to both ends of the hammer, with end sections extending vertically in opposite directions from their points of connection to the hammer, both ends of the hammer move at equal rates of speed during the lifting and dropping movements thereof and tilting of the hammer, which would cause binding upon the guides, is eliminated.

Another important object of the invention is to provide novel automatically operable means for admitting fluid under pressure to the cylinders simultaneously to raise the hammer, with manually controlled means for releasing the fluid pressure from the cylinders to permit the hammer to drop. In the construction illustrated herein fluid under pressure, such as compressed air, is supplied from a suitable source through a cylindrical inlet conduit 41 having a section which desirably extends horizontally through the base of the machine to a valve block 42 which is mounted upon the rear face of the base 1 as shown in dotted lines in Fig. 1 and in Fig. 6. In order to permit the use of rotatable valves of a convenient diameter, the valve block 42 is provided with a recess having a circular inlet end complementary to and registering with the inlet conduit 41, and tapering therefrom to a relatively wide somewhat elliptical outlet 43 as shown in dotted lines in Fig. 5 which communicates with a similar outlet in a horizontal valve sleeve 44 which is mounted in the valve block 42. A main operating three-way valve 45, which is rotatably

mounted in the sleeve 44, is provided with a passage 46 which extends diametrically therethrough and also has a port 47 which extends radially from said passage at right-angles thereto, as illustrated in Figs. 7 and 8 of the drawings. The valve 45 is provided at its ends with trunnions which desirably are mounted in anti-friction bearings 48 in the sleeve 44 as shown in dotted lines in Fig. 5. The main operating valve 45 and its antifriction bearings are of the same construction as the operating or control valve shown and described in our prior Patent No. 1,924,545 and particularly as shown in Figs. 10 and 11 of said patent.

An exhaust valve mechanism which is also mounted in the valve block 42 in proximity to the main operating valve and as shown in Figs. 7 and 8 comprises a sleeve 49 having diametrically opposite ports which communicate respectively through a port 50 with a corresponding port in the sleeve 44 and with a discharge outlet conduit 51 which may be provided with a flange 52, as shown in Fig. 5 to enable it to be connected to a suitable exhaust pipe. The exhaust valve 53 is of cylindrical form and is provided with diametrically opposite ports 54 and 55 which register respectively with the conduit 50 and the outlet 51. The port 55 of the exhaust valve 53 desirably is of substantially triangular form, as shown in Fig. 9, and may be rotarily adjusted to determine the effective size of the exhaust outlet, thereby controlling the rate at which the fluid under pressure is permitted to escape from the cylinders. The exhaust valve 53 desirably is provided with trunnions which are mounted in anti-friction bearings 56 which in turn are mounted in the sleeve 49, as shown in dotted lines in Fig. 5, and one of the trunnions of the exhaust valve is provided with an angular end portion 57, see Fig. 6 upon which a handle member 58 is secured, which may be conveniently moved manually to adjust the area of the exhaust outlet.

The valve block 42 is provided with a downwardly extending passage 59 which communicates with branches 60 and 61 which in turn communicate with conduits 62 and 63 leading to the lower end portions of the cylinders 19 and 20, as shown in Fig. 5 and in dotted lines in Fig. 1.

In the construction disclosed manually controlled pneumatically operated means are provided for actuating the operating valve 45. The preferred mechanism illustrated comprises an integral metal block 64 which is secured to the end of the valve block 42, as shown in Fig. 5, and is provided with integral vertical aligned cylinder extensions 65 and 66, the cylinder 65 having a smaller diameter than that of the cylinder 66. A piston 67 in the cylinder 65 is connected to one end of a piston rod 68, the other end of said piston rod being connected to the piston 69 in the cylinder 66. The piston rod is provided centrally of its length with enlarged annular sections between which complementary semi-cylindrical sections 70 of an actuating arm 71 are secured. As shown in Fig. 6 the arm 71 extends between rollers 72 and 73 which extend inwardly from a plate 74 which is fixedly mounted upon an angular extension 75 of one of the trunnions of the operating valve 45. A small pipe 76 leads from the main inlet conduit 41 through a manually operable rotary three-way valve 77 to the lower end of the cylinder 66, as shown in Fig. 1, and a similar small pipe 78 also leads from the main conduit 41 to the upper end of the cylinder 65. The valve 77 is provided with a manually operable handle 79.

By reason of this construction the cylinder 65 is supplied constantly with fluid under pressure. When the controlling valve 77 is positioned by the handle 79 to permit the passage of fluid under pressure from the source of fluid under pressure through the pipe 76 to the cylinder 66, the fluid pressure upon the piston 69 will force the piston upwardly against the constant pressure upon the piston 67 because of the greater area of the piston 69. It will therefore raise the arm 71 which is secured to the piston rod 68 and thereby rotate the main operating valve 45 to the position illustrated in Fig. 8 in which fluid is allowed to escape from the lifting cylinders 19 and 20 through the exhaust valve 53. The three-way controlling valve 77 is provided with a port which when the valve is restored manually to normal position communicates with an outlet 80 in the valve casting through which air under pressure escapes from the section of the pipe leading from the valve 77 to the cylinder 66. When therefore pressure in the section of the pipe 76, leading from the valve 77 to the cylinder 66, is released, the constant fluid pressure which is supplied to the cylinder 65 will force the piston 67 downwardly, thereby causing the piston rod 68 to rotate the main operating valve 45 to the normal position illustrated in Fig. 7, thereby supplying air under pressure from the inlet conduit 41 through the ports of the valve 46 and 47 to the cylinders 19 and 20 thereby raising the piston rods 22 thus lifting the hammer and maintaining it in raised position until the control valve 77 is again actuated manually to release the pressure in the lifting cylinders and permit the hammer to drop.

Assuming that the hammer is resting upon the anvil, the operator in starting the machine will rotate the handle 79 in a direction to cause the valve 77 to exhaust through the port 80 so that air under pressure will be released from the cylinder 66 thereby permitting the pressure on the piston 67 in the cylinder 65 to rotate the main operating valve to the position illustrated in Fig. 7 in which fluid under pressure is supplied to the lifting cylinders 19 and 20. The pistons of said cylinders will thereupon be raised, thus forcing the piston rods 21 and 22 upwardly and lifting the hammer.

When it is desired to drop the hammer the handle 79 will be rotated in the opposite direction thereby supplying fluid under pressure through the pipe 76 to the upper cylinder 66 so that the piston 69 will be forced upwardly by the pressure in the cylinder 66 and the main operating valve 45 rotated to exhaust position as shown in Fig. 8.

Desirably means are provided for admitting air under pressure to the cylinders 19 and 20 just previously to the impact of the hammer upon the anvil for the purpose of preventing a secondary blow caused by the rebound of the hammer, and also for the purpose of applying lifting force to the hammer upon its rebound, thereby saving a considerable amount of energy which otherwise would be required to lift the hammer from the position of rest. This is accomplished in the present construction by providing the controlling valve 77 with a vertical valve stem 81 having secured to it an inclined or preferably spiral cam 82 adapted to be engaged by one of the guideways 83 of the hammer or a suitable pin or lug 82x projecting therefrom. The cam 82 is adapted to be adjusted vertically upon the valve stem 81 in such manner as most effectively to cause admission of air under pressure to the lifting cyl-

inders 19 and 20 at the proper moment during rebound of the hammer.

In the operation of the drop hammer therefore the movement of the handle 79 in a proper direction will cause the hammer to drop, and as the hammer descends the cam 82 will be engaged by the pin 82x on the hammer at the proper time to rotate the controlling valve 77 to exhaust position, thereby releasing fluid pressure from the cylinder 66 through the pipe 76 to cause the rotation of the main operating valve 45 to the position shown in Fig. 7 in which air will be supplied to the lifting cylinders, thus causing the hammer automatically to be raised and maintained in raised position so long as air under pressure is supplied to the cylinders 19 and 20.

Desirably means are provided for cushioning upward movement of the hammer and to prevent vibration thereof when it is in lifted position. In the preferred construction illustrated fluid operated cushioning means are provided comprising a cylinder 84 extending upwardly from and preferably integral with the central portion of the beam 8 and provided with a head 85. A piston 86, which is reciprocably mounted in the cylinder 84, is provided with a piston rod 87, the lower end of which is adapted to be engaged by an abutment upon the hammer. In the particular construction shown the abutment comprises a head 88 of a screw 89 which extends into an axial bore in the central boss 12 of the hammer. The screw 89 is provided with a nut 90 having suitable spanner holes 91 by means of which it may be rotated to adjust the position of the head 88 of the screw. The piston rod 87 may be provided with a suitable gland 92 to prevent escape of fluid under pressure from the cylinder along the piston rod 87. Fluid under pressure is led from the main pipe 41 through a branch (not shown) to a pipe 93 having branches 94 and 95 leading respectively to the upper and lower portions of the cylinder 84. The branch 94 of the pipe 93 desirably is provided with a valve 96 which may be adjusted to restrict the rate of passage of the fluid under pressure from the upper section of the cylinder 84.

When in the operation of the machine the hammer is in lowered position the piston 86 and its piston rod 87 will descend by reason of the fact that the air under pressure supplied on opposite sides of the piston 86 through the pipes 94 and 95 will be equal and the weight of the piston and piston rod sufficient to cause it to descend. Upon upward movement of the hammer the head 88 of the screw 89 will engage the lower end of the piston rod 87 and during further upward movement of the hammer the piston 86 will be forced upwardly, thereby forcing air under pressure through the pipe 94 and the restricted passage produced by the valve 96, thereby cushioning the upward movement of the hammer and gradually causing it to come to rest without jarring the superstructure of the frame.

While the particular invention illustrated and described herein comprises two lifting cylinders having pistons acting upon the respective end portions of the hammer, with means operable when the hammer is lifted or permitted to drop to equalize the rate of movement of the ends of the hammer, it is obvious that the equalizing mechanism will operate effectively if only a single cylinder is supplied with fluid under pressure to lift the hammer, or if the lifting force is applied to the hammer by any means at any point or points throughout the length thereof. It is

also obvious that similar equalizing means may be applied to the hammer transversely of its width to prevent lateral tilting of the hammer within the spirit and scope of the invention.

By reason of the present invention therefore a drop hammer construction is provided in which the hammer and anvil may be of any desirable size or length and in which proper vertical movements of the hammer without binding upon its guides is insured. As a consequence, the drop hammer may be constructed of much larger capacity than any which have heretofore been produced and by reason of the automatic control of the fluid pressure for lifting the hammer, most effective operation is insured.

Another important object of the invention is to provide a novel process of producing an anvil die and a complementary hammer die in such manner as to provide uniformity of the complementary co-acting die surfaces and to insure accuracy of registration of all portions of the hammer die with those of the complementary anvil die.

The anvil die may be constructed as heretofore described by casting the zinc or bronze composition in a matrix of plaster of Paris and then removing the matrix and turning over the die and securing it upon the anvil.

Figs. 10 and 11 of the drawings illustrate a drop hammer having an anvil provided with an anvil die and a hammer similar to that heretofore described with the exception of the omission of the transverse reenforcing web 15 and showing the manner in which the hammer die is cast directly upon the hammer.

In order to prevent displacement of the anvil die upon the anvil the upper surface of the anvil desirably is provided with a series of grooves 97 extending both longitudinally and transversely over a somewhat larger area than the under surface of the anvil die.

A vertical frame 98 of suitable material is then placed upon the anvil closely surrounding the periphery of the anvil die and desirably has extensions which project into the grooves 97 of the anvil die to hold the frame in place. The frame 98 extends above the upper surface of the anvil die the necessary distance to provide for the proper depth of the hammer die. The body of the hammer 9 is provided with a sufficient number of properly distributed holes to receive anchoring bolts 99 the heads of which extend a considerable distance below the under face of the hammer head. The hammer is also provided with inverted conical sprue holes 100 through which the lead, or other relatively soft metal may be poured into the frame which surrounds the anvil die.

In forming the hammer die the hammer is lowered gently until it rests upon the upper edge of the frame 98, with the bolts 99 depending into the space between the hammer and the upper surface of the anvil die. The molten lead, or other relatively soft metal, is poured through the conical sprue holes 100 until the entire chamber within the frame is filled and until the metal overflows through the sprue holes. Any number of such sprue holes may be employed and the metal poured through them simultaneously or as rapidly as possible to produce an integral anvil die of uniform consistency.

In previous processes of casting a hammer die upon a hammer, a plate provided with dovetail recesses has been secured to the under face of the hammer and after the chamber of the frame

has been filled with molten metal the hammer is lowered until the metal is forced into the dovetail recesses and the hammer permitted to remain in such position until the metal is cool.

5 This method is objectionable for the reason that the pressure of the hammer frequently causes the excess of molten metal in the frame to be squirted out thus endangering the operator. Furthermore, the lowering of the cold hammer upon the molten metal chills the upper surface thereof. This method is further objectionable in that it is very difficult to remove the soft metal die from the plate to which it is secured by the insertion of wedges in the grooves which are 10 likely also to distort the die and unfit it for further use.

By the present method the heat of the metal transmitted to the hammer during the pouring operation sufficiently heats the metal of the 15 hammer to reduce the chilling effect upon the molten metal to a minimum. Furthermore, the conical sprue holes provide risers which enable all of the air to escape from the chamber of the frame, thereby insuring complete filling of the frame and homogeneity of the metal of the hammer die.

Inasmuch as the hammer is stationary during the pouring operation, all danger of squirting of the metal by the previous process above described is avoided.

20 By reason of the present invention the hammer die can be readily removed from the hammer by merely removing the nuts of the bolts and raising the hammer and when it is desired to 25 replace the die the bolts will register with the holes and any slight deviation will be compensated by the engagement of the metal forming the conical protuberances 101 with the complementary walls of the sprue holes 100 through 30 which the metal has been poured.

35 By reason of the present method therefore the hammer die can be more safely made and when constructed in this manner is of a more homogeneous character than those produced by previous methods. It is also easily adapted for removal and replacement without distortion, and 40 accuracy of operation thereby insured.

When the hammer die has been formed in the above manner, the hammer is raised, the frame 45 98 removed, and the hammer then permitted to drop upon the anvil die. Such dropping of the hammer will force the anvil die downwardly so that the metal of the under face of the anvil die will be driven into the recesses 97 in the anvil, thereby fixedly positioning the anvil in place and 50 insuring perfect registry with the hammer die during the die-shaping of the blanks of metal which are placed upon the anvil die.

55 It will be understood that the particular embodiment of the invention shown and described herein is of an illustrative character and is not restrictive of the meaning and scope of the following claims.

Having thus described the invention, what is 60 claimed as new, and desired to be secured by Letters Patent, is:

65 1. A drop hammer construction comprising a base having an anvil, a frame mounted on said base having widely spaced vertical guides for the ends of the hammer, an unsymmetrically weighted hammer reciprocably mounted in said guides, vertical pneumatic cylinders mounted respectively on the end portions of said base having pistons provided with upwardly extending piston rods engaging the respective end portions of the 70 75

hammer, means for supplying air under pressure to said cylinders to cause the pistons thereof to push the hammer upwardly, manually operable means for simultaneously releasing the air under pressure from said cylinders to permit the hammer to drop, and means for transmitting force from one end of the hammer to the other to equalize the rate of movement of the guided end portions of the hammer throughout the lifting and dropping movement thereof.

2. A drop hammer construction comprising a base having an anvil, a frame mounted on said base having widely spaced vertical guides for the ends of the hammer, an unsymmetrically weighted hammer reciprocably mounted in said guides, vertical pneumatic cylinders mounted respectively on the end portions of said base having pistons provided with upwardly extending piston rods engaging the respective end portions of the hammer, means for supplying air under pressure simultaneously to said cylinders to cause the pistons thereof to push the hammer upwardly, manually operable means for simultaneously releasing the air under pressure from said cylinders to permit the hammer to drop, complementary inextensible flexible power transmitting means each connected to both ends of said hammer, and means for guiding the same to cause said inextensible members to act upon the end portions of the hammer in opposite directions during the lifting and dropping movement thereof thereby to equalize the rates of movement of the ends of the hammer and to prevent binding action between the respective ends of the hammer and the guides.

3. A drop hammer construction for shaping large unsymmetrical articles comprising a base provided with an anvil having an unsymmetrical die mounted thereon, a frame having vertical standards extending upwardly from said base and provided with guides for the hammer, a cross beam connecting the upper ends of said standards, a hammer reciprocably mounted in said guides, carrying an unsymmetrically weighted die complementary to said anvil die, vertical pneumatic cylinders mounted on the end portions of said base having pistons provided with upwardly extending piston rods connected respectively to the end portions of the hammer, means for simultaneously supplying air under pressure to said cylinders to raise said hammer, means for releasing said air under pressure from said cylinders to permit the hammer to drop, upper sheaves mounted on said frame above the respective ends of said hammer, a lower sheave mounted upon the lower portion of one of said standards, and a taut inextensible flexible member connected at one end to the end portion of said hammer and extending vertically upwardly therefrom over an upper sheave, thence horizontally over the other upper sheave, thence downwardly around the lower sheave, and thence vertically upwardly and connected at its end to said hammer, and operable during the movement of the hammer to equalize the rates of movement of the ends of said hammer.

4. A drop hammer construction for shaping large unsymmetrical articles comprising a base provided with an anvil having an unsymmetrical die mounted thereon, a frame having vertical standards extending upwardly from said base and provided with guides for the hammer, a cross beam connecting the upper ends of said standards, a hammer reciprocably mounted in said guides, carrying an unsymmetrically weighted

die complementary to said anvil die, vertical pneumatic cylinders mounted on the end portions of said base having pistons provided with upwardly extending piston rods connected respec-

5 tively to the end portions of the hammer, means
for simultaneously supplying air under pressure
to said cylinders to raise said hammer, means for
releasing said air under pressure from said cylinders
to permit the hammer to drop, upper sheaves
10 mounted on said frame above the respective ends
of said hammer, a lower sheave mounted upon
the lower portion of one of said standards, and
a taut inextensible flexible member connected
at one end to the end portion of said hammer
15 and extending vertically upwardly therefrom over
an upper sheave, thence horizontally over the
other upper sheave, thence downwardly around
the lower sheave, and thence vertically upwardly
and connected at its end to said hammer, and
20 a complementary taut inextensible flexible member
reversely connected in like manner to the
ends of said hammer and passing over similar
upper sheaves and a lower sheave mounted upon
the opposite standard.

25 5. A drop hammer construction comprising a frame having vertical guides for the hammer, a hammer reciprocably mounted in said guides, means for lifting said hammer including a cylinder and piston, an inlet conduit leading from a
30 supply of air under pressure to said lifting cylinder, an operating valve in said conduit having ports respectively to establish communication between said supply and said cylinder and to exhaust the fluid pressure from said cylinder,
35 means for positioning said operating valve comprising oppositely disposed cylinders of different diameter provided respectively with pistons having a common piston rod having means for actuating said valve, means for simultaneously
40 supplying air under the same pressure from said supply of air under pressure to both of said cylinders operable by the greater effective pressure on the larger piston so to position said operating valve as to supply fluid under pressure to
45 said lifting cylinder, and manually operable means for releasing the fluid under pressure from the larger cylinder only to cause the fluid pressure in the smaller cylinder to move the operating valve to exhaust position.

50 6. In a drop hammer construction comprising
a base provided with an anvil, a frame having
vertical standards extending upwardly from said
base and provided with guideways for a ham-
mer, a hammer reciprocably mounted in said
guideways, pneumatically operable means
55 mounted on end portions of said base having
means for simultaneously raising both ends of
said hammer, means for supplying air under
pressure to said pneumatically operable means,
60 and means for releasing the fluid pressure from
said pneumatically operable means to permit the
hammer to drop, means for cushioning and ar-
resting the upward movement of said hammer
comprising a cylinder mounted on said frame
65 having a piston reciprocable therein provided
with a piston rod extending into the path of said
hammer, means for supplying fluid under pres-
sure to said cylinder comprising branch pipes
communicating with said means for supplying
70 air under pressure and having branches com-
municating respectively with the upper and low-
er chambers of said cylinders above and below
its piston, and adjustable means in the branch
leading to the upper chamber for restricting the
75 passage of air under pressure therethrough op-

erable when the piston is forced upwardly by engagement of the hammer with said piston gradually to arrest the upward movement of said hammer by restricting the flow of fluid through the branch conduit leading to the upper chamber of the cylinder and upon equalization of the pressure in said upper and lower chambers of the cylinder to permit said piston and piston rod to descend to normal position by virtue of the weight of said piston and piston rod.

7. A drop hammer construction comprising a base provided with an anvil, a frame having vertical standards extending upwardly from said base and provided with a guideway for the hammer, a cross beam connecting the upper ends of said standards, a hammer reciprocably mounted in said guides, vertical cylinders mounted on the ends of said base each having a piston provided with a vertical piston rod connected to an end portion of the hammer, means for supplying fluid under pressure simultaneously to said cylinders to raise the hammer, means for simultaneously releasing the fluid pressure in said cylinders, and means for cush-

ioning and arresting the upward movement of said hammer comprising a cylinder mounted upon said beam midway of its width having a piston reciprocable therein provided with a piston rod extending into the path of the hammer, means for supplying fluid under pressure to said cylinder comprising a pipe leading from said fluid pressure supply and having branch pipes communicating respectively with the upper and lower ends of said cylinder, and adjustable means for restricting the passage of said fluid under pressure through the pipe which communicates with the upper end of said cylinder.

10 8. A drop hammer construction as in claim 7, characterized in that the hammer is provided with an upwardly extending boss, a screw mounted in said boss having a head forming an abutment to engage the lower end of the piston rod of the piston of the cushioning means and a nut for said screw mounted upon the upper end of said boss.
